WITNESS:

George I. DesChamps INVENTOR
BY Victor J. Evans

ATTORNEY

UNITED STATES PATENT OFFICE.

GEORGE I. DES CHAMPS, OF LEWISTON, IDAHO.

ROTARY VALVE.

Application filed April 17, 1920. Serial No. 374,654.

To all whom it may concern:

Be it known that I, GEORGE I. DES CHAMPS, a citizen of the United States, residing at Lewiston, in the county of Nez 5 Perce and State of Idaho, have invented new and useful Improvements in Rotary Valves, of which the following is a specification.

This invention relates to improvements in valves especially designed for internal combustion engines and aims to provide a rotary valve for controlling both the intake and exhaust ports of the engine.

Another object of the invention is the provision of a novel arrangement of valve packing, to prevent leakage around the ports and thus increase the efficiency of the engine.

Another object is the provision of a valve of this character which is exceedingly simple in construction and operation and by 20 means of which the power of the engine will be materially increased and a smooth, even and quiet operation assured.

Other objects and advantages of the invention will appear as the following description is read in connection with the accompanying drawings.

In the drawings:—

Figure 1 is a fragmentary section through the upper end of the cylinder of an engine 30 with the valve applied thereto, the latter being in position to admit a charge of fuel to the cylinder.

Figure 2 is a section taken longitudinally of the cylinder and transversely of the valve 35 with the ports in the position shown in Figure 1.

Figure 3 is a view similar to Figure 1 with the valve in position for the escape of the exhaust gases.

Figure 4 is a view similar to Figure 2 with the ports in the position shown in Figure 3.

Figure 5 is a detailed view looking at the end of the valve casing with the end plate removed.

Figure 6 is an inner face view of the end plate for closing the end of the casing shown in Figure 5.

Figure 7 is a section on the line 7—7 of Figure 5.

Figure 8 is a view looking at the opposite end of the valve casing from that shown in Figure 5.

Figure 9 is an inner face view of the end plate for closing the end of the cylinder 55 shown in Figure 8.

Figure 10 is a diametric view showing the

relative diameters of the bore of the casing and the casing packing plate.

Figure 11 is a view showing the relative 60 diameters of the outer periphery of the rotary valve member and a packing plate for said member.

Figure 12 is a detailed elevation of the rotary valve member with its packing plate 65 in position.

Referring to the drawings in detail, wherein like characters of reference denote corresponding parts, the reference character 15 indicates a cylinder of an internal combustion engine which has formed therewith 70 or connected thereto a casing 16 which is disposed transversely of the end of the cylinder and with which it communicates by means of a port 17. This casing is provided with spaced walls so as to form water circulating 75 chambers 18 which communicate with chambers of the water jacket of the engine. The casing 16 provides a casing for the rotary valve member 19, the latter being of hollow formation and divided longitudinally by 80 means of a partition 20. The valve member 19 has extending from each end thereof a short shaft 21 and these shafts have bearings in opposite end plates 22 and 23. Both of these end plates are provided with water 85 chambers 24 which communicate with the chambers 18 through openings 25 so that a system of water circulation is provided which acts to maintain a proper degree of 90 temperature for the proper operation of the valve. Interposed between the end plates 23 and the adjacent ends of the valve member 19 are packing rings 26 and gaskets 27, while a gasket 28 is provided between the end plates and shoulders formed within the casing 16.

The end plate 23 is spaced from the end of the casing 16 and this end is closed by a plate 28' so as to provide a housing for a gear 29 which is carried by one of the short shafts 21 of the valve member 19 and 95 a gear 30 operated through a suitable connection with the crank shaft of the engine. The lower wall of the valve casing beneath the gear 29 is formed as shown at 31 to provide an oil chamber into which the periphery of the gear 29 extends so as to provide proper lubrication to the gears 29 and 30.

The valve member 19 is provided upon opposite sides of the partition 20 with ports 32 and 33. These ports are adapted to be 100 brought into register with a port 17, the port 32 providing an intake port while the

- port 33 provides an exhaust port, so that the space upon opposite sides of the partition 20 within the valve member 19 is divided into an intake chamber 34 and an exhaust chamber 35. The intake chamber 34 is also provided with a port 36 which is in a line with the port 32 and is adapted to register with a port 37 in the intake manifold 38 of the engine when the ports 32 and 17 register.
- 10 The ends of the intake chamber 34 are closed, while one end of the exhaust chamber 35 is open to provide a port 39, so that communication may be established between the exhaust chamber and an exhaust manifold 40.
- 15 The ports 32, 33, 17, 36 and 37 are provided with a packing of novel formation which prevents leakage of the gases and insures a proper operation of the engine. For 20 this purpose the bore of the valve casing 16 is cut away as shown at 41 for the reception of a packing plate 42 which is of segmental cross sectional shape, the diameter of its inner face being greater than the diameter 25 of the bore of the valve casing. This plate 42 is provided with openings 43 whose area is slightly greater than the area of the ports 17 and 37 which they are adapted to surround. The ports 17 and 37 are provided with 30 flanges 44 which surround these ports and extend within the bore of the valve casing and enter the openings 43 in the plate 42 and are flushed with the inner face of this plate.
- 35 The rotary valve member 19 is also cut away as shown at 45 for the reception of a segmental packing plate 46, the outer diameter of which is less than the outer periphery of the rotary valve member 19.
- 40 Like the plate 42 it is provided with openings 46' which surround the ports 32, 33 and 36 and receive flanges 47 which surround the said ports. The plates 42 and 46 are formed of resilient metal and have their 45 greatest thickness along their longitudinal center so as to increase the strength of the plates at this point to overcome the weakening effect of the openings provided in the plates.
- 50 The opposite side edges of the plates 42 and 46 are curved and inclined with respect to the length of the casing and valve member, so that the edges of these plates will meet with a shearing action during the rotation of the valve member and prevent

any possibility of the edge of the plates 55 catching upon one another. It will be apparent that the relative diameters of the plates, the casing bore and the valve member will insure an absolutely tight packing around the various ports. For the purpose 60 of further increasing the efficiency of the engine, the bore of the cylinder and the bore of the valve casing are substantially the same and the area of the ports relatively large so that free passage of the fuel and 65 exhaust gases is assured.

The invention is susceptible of various changes in its form, proportions and minor details of construction and the right is herein reserved to make such changes as properly fall within the scope of the appended 70 claim.

Having described the invention what is claimed is:—

A rotary valve for internal combustion engines, comprising a horizontal casing having a cylindrical bore and provided with intake and exhaust ports, said casing having water chambers in communication with the water jacket of said engine, and having a port in 75 communication with the cylinder of said engine, spaced plates secured to the inner walls of said casing, having water chambers formed therein in communication with the water chambers in said casing, and provided with aligned openings, a hollow rotary valve member located in said casing spaced from one of said plates, having a port in 80 one end adapted to communicate with the exhaust port of said casing and provided with a port in one side thereof adapted to communicate with the intake port of said casing, relatively short shafts extending from opposite ends of said valve member 85 and journalled in the openings in said plates, a partition disposed longitudinally in said valve member between said port, said valve member having ports upon opposite sides of 90 said partition adapted to communicate with the cylinders of said engine, a plate secured to one end of said casing, a gear carried by one of said shafts, between the last mentioned plate and one of the first mentioned plates, and a gear meshing with the gear aforesaid for the purpose specified. 100

In testimony whereof I affix my signature.

GEORGE I. DES CHAMPS.
